HANDLE CONSTRUCTION FOR FLY SWATTERS AND THE LIKE

Adolph F. Shafter, Decatur, Ill., assignor to U. S. Manufacturing Corporation, Decatur, Ill., a corporation of Illinois

Application June 27, 1935, Serial No. 28,659

12 Claims. (Cl. 43—137)

This invention relates to improvement in handle construction for fly swatters and the like, and the principal object is the provision of a construction which is simple and easy to manufacture, attractive in appearance, strong in construction, and at the same time has the requisite resiliency or flexibility for proper use.

Another object of this invention is the provision of a handle construction which is formed of a single piece of metal having one end looped or turned around a gripping element and having the other end split and forked to provide means whereby it may be secured to a fly swatter or other implement.

15 Other objects include improvements in detail of construction whereby a very effective device of the character described is provided.

To the accomplishment of the foregoing and such other objects as may hereinafter appear, this invention consists in the construction, combination and arrangement of parts hereinafter described and then sought to be defined in the appended claims, reference being had to the accompanying drawing forming a part hereof and which show, merely for the purpose of illustrative disclosure, a preferred embodiment of my invention, it being expressly understood, however, that various changes may be made in practice within the scope of the claims without digressing from my inventive idea.

In the drawing—

Figure 1 represents a perspective view of one form of device constructed to embody my invention.

35 Figure 2 is an elevation of the same device taken from the opposite side of Figure 1.

Figure 3 is a vertical section taken substantially on line 3—3 of Figure 2.

Figure 4 is an enlarged view taken in section 40 through the gripping element to show the manner of connecting the gripping element and the handle.

Fig. 5 is a detailed view of a slight modification.

45 Referring now to the drawing, the handle member is designated generally by the reference character 1 and is formed to provide a gripping part 2 and at the other end a securing part 3 whereby a fly swatter 4 or any other implement or utensil may be connected or attached thereto.

50 This handle member 1 is preferably in the form of a flat piece of material, preferably of steel, with the securing part split as at 5 for a substantial distance from that end of the handle and with the split parts 5' bent at an angle

to form a V, as clearly shown in Figures 1 and 2. This V shaped end part 3 is adapted to be positioned within the folded lower end of the fly swatter body 4 and the parts held together by means of rivets, staples and the like 6.

The gripping end of the handle is preferably made in the form of a loop 7 by bending the metal at right angles at 8, 9, 10, 11, 12 and 13. This forms an open loop substantially rectangular in shape and the free end 14 of the handle member is secured to the handle member proper. In the form shown in the drawing this connection is made by splitting the free end of the metal at 15 and bending the two prongs or fingers 16 around the handle member as clearly shown in Figures 1, 2 and 4. It is to be understood that this is merely one method of connecting these parts together and that it may be accomplished by spot welding, riveting or in other ways as long as a closed gripping loop is provided.

It is to be understood that the gripping loop 7 may serve as a means whereby the implement or utensil is held by the user or operator, or a gripping element 17 may be positioned within said loop 7. This gripping element may be provided with a groove 18 around the sides and ends thereof, which groove is adapted to receive the open loop metal gripping element 7 and thereby hold the parts together with the gripping element 17 within the loop 7. This gripping element may be made of any suitable material such as wood, composition and the like, and may be provided with the opening 19 or the loop or staple 20 for hanging purposes.

The handle is preferably made of flat metal as illustrated, but this metal may be of other shapes. It provides sufficient strength and also the requisite resiliency and elasticity for use with fly swatters, as well as other implements and utensils. The means whereby the handle is connected to the implement is simple, effective and strong, particularly as it gives an extended bearing between the parts. The gripping loop with the gripping element held therein gives an effective means for connecting these parts, at the same time retaining simplicity of construction.

What I claim is:

1. A handle for implements and utensils comprising an elongated metallic element having one end split and bent to form a pair of angularly disposed arms to form attaching means for the implement or utensil and having its other end bent and formed into an open loop.
2. A handle for implements and utensils com-

prising an elongated metallic element having one end split and bent to form a pair of angularly disposed arms to form attaching means for the implement or utensil and having its other end 5 bent and formed into an open loop with a gripping element held within and by said loop.

3. A handle for implements and utensils comprising an elongated metallic element having one end split and bent to form a pair of angularly 10 disposed arms to form attaching means for the implement or utensil and having its other end bent and formed into an open loop with the end of the handle member secured to the handle member proper near the upper end of said 15 loop.

4. A handle member for implements, utensils and the like comprising an elongated flat metal member having one end split so as to provide two arms, said arms being bent at an angle to 20 form a V shaped securing end for the handle member, the other end of the handle member being bent to form an open rectangular loop with the extreme end thereof secured to the handle member proper.

25 5. A handle member for implements, utensils and the like, comprising an elongated flat metal member having one end split so as to provide two arms, said arms being bent at an angle to form a V shaped securing end for the handle 30 member, the other end of the handle member being bent to form an open rectangular loop with the extreme end thereof being formed with a pair of bendable fingers which are bent around the handle member proper to form a permanent 35 connection.

6. A handle member for implements, utensils and the like, comprising an elongated flat metal member having one end split so as to provide two arms, said arms being bent at an angle to 40 form a V shaped securing end for the handle member, the other end of the handle member being bent to form an open rectangular loop with the extreme end thereof being secured to the handle member proper and a gripping ele- 45 ment positioned within and secured to said open loop.

7. A handle for implements and utensils, comprising an elongated, flat, resilient metallic element having its upper end split for a substantial 50 distance to provide two arms, said arms being bent at an angle to each other to form a V-shaped securing portion, and said arms being flat on both sides and thin.

8. A handle member for implements, utensils and the like, comprising an elongated flat metal member having its upper end formed to provide a securing end portion adapted to be connected to an implement or utensil, the other end of the handle member being bent to form an open rectangular loop with its inner surface flat, and a gripping element positioned within and secured to said open loop with the flat face of the open loop in engagement with the side faces of 10 the gripping element.

9. A handle member for implements, utensils and the like, comprising, an elongated flat metal member having its upper end formed to provide a securing end portion adapted to be connected 15 to an implement or utensil, the other end of the handle member being bent to form an open rectangular loop with its inner surface flat, the end of said open loop portion of the handle member being split to form two fingers which are bent around the body of the handle member to form said open loop, and a gripping element positioned within and secured to said open loop with the flat face of the open loop in engagement with the side faces of the gripping 20 element.

10. A handle member for implements and utensils comprising an elongated metal member having one end bent to form an open loop, the extreme end of said loop being formed with 30 bendable fingers which are bent around said metal member to form a connection therewith.

11. A handle member for implements and utensils comprising an elongated metal member having one end bent to form an open loop, the extreme end of said loop being secured to 35 said metal member to form a connection therewith and a gripping element positioned within and secured to said open loop.

12. A handle member adapted for use with fly swatters, said handle member being in the form of an elongated flat thin metal member having its upper end split to provide a pair of arms, said arms being bent away from each other to form a substantially V-shaped securing end, said arms being thin and both sides of said arms being flat so as not to substantially increase the total thickness of the lower end portion of the body of a fly swatter body adapted 45 to be attached to said handle member.

ADOLPH F. SHAFTER.
